(57) **CLAIM**

The ornamental design for a mobile phone, as shown and described.

DESCRIPTION

FIG. 1 is a front perspective view of a mobile phone; FIG. 2 is a rear perspective view of the mobile phone of FIG. 1;

FIG. 3 is a front view of the mobile phone of FIG. 1; FIG. 4 is a rear view of the mobile phone of FIG. 1; FIG. 5 is a top plan view of the mobile phone of FIG. 1; FIG. 6 is a bottom plan view of the mobile phone of FIG. 1; FIG. 7 is a left-side view of the mobile phone of FIG. 1; FIG. 8 is a right-side view of the mobile phone of FIG. 1; FIG. 9 is a front perspective view with the mobile phone in an alternate position;

FIG. 10 is a rear perspective view with the mobile phone in the position of FIG. 9; and,

FIG. 11 is a front perspective view with the mobile phone in another alternate position.

The present article is a mobile phone, wherein a member having an arm-like shape to which a wheel member is attached a tip portion thereof (arm with a wheel) is attached to each side surface of the mobile phone, a member to which a wheel is added to a central lower portion of the mobile phone, and a motion like a robot can be automatically performed by using at least one of the arms with a wheel and the member to which a wheel is attached.
